US00D476753S

(12) United States Design Patent **(10) Patent No.:** **US D476,753 S**
Chelf et al. **(45) Date of Patent:** **** Jul. 1, 2003**

(54) FLUORESCENT LIGHT FIXTURE

D418,936 S * 1/2000 Dunning D26/3
D448,499 S * 9/2001 Choi D26/3

(75) Inventors: **Bentley Chelf**, Laguna Nigel, CA (US);
Wang Liang Chou, Taichung (TW)

* cited by examiner

(73) Assignee: **General Innovations, LLC.**, Laguna
Nigel, CA (US)

Primary Examiner—Marcus A. Jackson

(74) Attorney, Agent, or Firm:—Haynes and Boone, LLP.

(**) Term: **14 Years**

(57) CLAIM

(21) Appl. No.: **29/159,685**

The design for the fluorescent light fixture, as shown and
described.

(22) Filed: **Apr. 24, 2002**

DESCRIPTION

(51) LOC (7) Cl. **26-06**

FIG. 1 is a isometric view of our new design;

(52) U.S. Cl. **D26/3**

FIG. 2 is a side elevational view;

(58) Field of Search D26/1, 2, 3, 4,
D26/26; 313/313, 315, 318, 485, 493, 567,
569, 578, 579, 580

FIG. 3 is an end elevational view;

FIG. 4 is a bottom plan view; and,

FIG. 5 is a top plan view.
